CONTROL MECHANISM FOR BOILERS

Andrew J. Faucher, Grand Prairie, Tex.

Application May 12, 1938, Serial No. 207,477

8 Claims. (Cl. 236—29)

This invention relates to new and useful improvements in control mechanism for boilers.

One object of the invention is to provide an improved control mechanism for boilers, which is responsive to changes in boiler pressure, whereby the operation of the boiler is accurately regulated and controlled in accordance with such pressure, which makes it possible to maintain a desired boiler pressure and temperature.

10 An important object of the invention is to provide an improved control mechanism for boilers wherein a single actuating member is utilized to control the fuel and air supplied to the burners, as well as to control the flue damper, whereby all of the adjustable elements which affect the 15 boiler operation are simultaneously adjusted and controlled; the single actuating member being operated by changes in conditions within the boiler, whereby the mechanism is entirely automatic in operation.

Another object of the invention is to provide a control mechanism, of the character described, wherein a pivoted master actuating member is employed, said member being operated by an improved pressure responsive means which is responsive to pressure changes within the boiler, whereby the member is automatically swung by a predetermined pressure condition.

A further object of the invention is to provide 30 an improved boiler control mechanism having an actuating member connected with and controlling the elements affecting the boiler operation, said member being operated by a pressure actuated plunger, which pressure is conducted 35 to the plunger from the boiler; there also being a pilot or control valve interposed between the pressure actuated plunger and the boiler for preventing the application of pressure to the plunger until a predetermined pressure is attained, whereby the plunger and actuating member are operated with a smooth and even action.

A construction designed to carry out the invention will be hereinafter described, together with other features of the invention.

45 The invention will be more readily understood from a reading of the following specification and by reference to the accompanying drawings, in which an example of the invention is shown, and wherein:

50 Figure 1 is an isometric view of a boiler having a control mechanism, constructed in accordance with the invention, attached thereto.

55 Figure 2 is a view partly in elevation and partly in section of the operating diaphragm and its associate parts,

Figure 3 is a plan view of the parts shown in Figure 2.

Figure 4 is a horizontal, cross-sectional view taken on the line 4—4 of Figure 2.

Figure 5 is an elevation of the master control bar and having portions thereof broken away to more clearly illustrate the invention.

Figure 6 is a transverse, vertical, sectional view taken on the line 6—6 of Figure 5.

Figure 7 is a view, partly in elevation and partly in section, of the pilot mechanism for controlling the admittance of pressure to the operating diaphragm.

Figure 8 is a horizontal, cross-sectional view taken on the line 8—8 of Figure 7.

Figure 9 is a horizontal, cross-sectional view taken on the line 9—9 of Figure 7, and

Figure 10 is a transverse, vertical, sectional view taken through the bleeder header.

In the drawings, the numeral 10 designates a boiler which may be of any desired construction. The boiler has the usual burners (not shown) therein and fuel is supplied to said burners through a fuel supply line 11 which extends through the front or end wall of the boiler housing. A suitable control valve 12 is connected in the line 11 and has a pivoted control arm 13 which is arranged to open or close the valve to control the flow of fuel to the burners. The usual air inlet louvers or doors 14 which control admittance of fresh air to the combustion chamber are located in the end wall of the housing, being hinged to swing on rods 15 in the usual manner. The end of the rod 15 of each door is extended and has an arm 16 secured thereto and the arms are connected by a link 17, whereby said arms are swung simultaneously. Manifestly, when the arms 16 are swung the rods 15 are rotated to swing the louvers or doors 14, whereby more or less air is admitted to the combustion chamber.

The boiler casing or housing has the usual flue 18 extending upwardly therefrom and a suitable damper 19 is mounted within the flue. The damper is secured to a shaft 19' which has one end projecting through the flue. This projecting end of the shaft is provided with an actuating arm 20 which may be swung to rotate the shaft and adjust the position of the damper. A weight arm 21 having a weight at its outer end is secured to the shaft and tends to hold the damper in its closed position.

As is well known, it is desirable in operating a boiler that when the fuel supply is varied, the air supply through the louvers 14, as well as the

position of the damper 19, be varied accordingly. Similarly, a change in the air supply or a variation in the position of the damper requires a change in fuel supply. Thus, in order to efficiently control the boiler, the fuel control valve 12, the louvers 14 and the damper 19 must be operated simultaneously in order that their relative positions to each other be maintained under all operating conditions.

10 For accomplishing the simultaneous operation of these elements, a master control bar 22 is pivotally mounted at one side on the boiler 10. This bar has one end overlying a block 23 which block is formed with ears 24 at one end. Tie bolts 25 extend upwardly through the block on each side of the bar and pass through a transverse retaining plate 26 which engages the top of the bar. The bolts receive nuts 27 and manifestly, said bolts and plate fasten the bar and block together.

15 The inner face of each ear 24 of the block is formed with a vertical recess 28 which recess has its lower end rounded, whereby an annular bearing element or ring 29 is insertable therein. An upstanding lug 30 is disposed between the ears 24 and a transverse shaft 31 is supported in said lug, the ends of said shaft being insertable within the bearing rings 29. The bottom of the shaft is sharpened to a knife edge (Figures 2 and 5) 20 and this edge rests on the inner periphery of the rings at the lower portion thereof, as will be explained.

25 The supporting lug 30 is formed integral with a collar 32 which encircles the upper end of a tubular sleeve or cylinder 33. The cylinder extends upwardly from a diaphragm case 34. As is clearly shown in Figure 2, the lug 30 overhangs the upper end of the cylinder so as to be supported thereby and the collar 32 may be fastened 30 to said cylinder by a set screw 35. A lateral arm 36 is preferably made integral with the collar and extends beneath the block 23 and bar 22. An adjustable bolt 37 is threaded through the arm and is arranged to be engaged by the 35 underside of the block to limit the downward swinging of the block and bar. An angular bolt 38 extends through the arm 36, being adjustably retained by nuts 38', and has its lateral extension overlying the top of the block for limiting upward 40 swinging of the block and bar.

45 From the foregoing, it is obvious that the block 23 which has the actuating bar 22 secured thereto is pivotally mounted on the shaft 31 and when the block is swung, said bar is also swung. For imparting movement to the block, a plunger 39 50 is disposed within the cylinder 33 and the lower end of the plunger rests upon a pressure responsive diaphragm 40 suitably clamped within the case 34. The upper end of the plunger has a 55 replaceable bearing cap 41 mounted thereon and said cap has an upstanding transverse fin 42 formed with a knife edge. The fin engages within a recess 43 provided in the underside of a bearing plate 44 which is fastened to the underside 60 of the block 23. The actuating bar 22 and block 23 are held in a lowered position, so that the plate 44 and fin 42 are in constant engagement, by a weight 45 which is adjustably mounted on the free end of the bar 22. With this arrangement 65 the weight 45 is constantly pulling the free end of the bar 22 downwardly with the result that the knife-edge fin 42 forms a fulcrum point, thereby swinging the pivoted end of the arm upwardly so that the knife edge of the shaft 31 70 is held in constant engagement with the inner

periphery of the bearing rings 29. The knife-edge bearing contacts or points reduce frictional wear in the mechanism and make the same more sensitive in operation.

5 The bottom of the diaphragm case 34 has a short pipe 46 connected therein and a T 47 is connected to the lower end of said pipe. A vertical standard 48 which extends upwardly from the floor, or other support, has its upper end fastened into the T and supports the diaphragm case 34, 10 cylinder 33 and their associate parts including the actuating bar. The lateral outlet of the T 47 has a pressure line 49 threaded thereinto and said line conducts pressure through the pipe 46 into the case below the diaphragm 40. 15

When the pressure acting against the diaphragm is sufficient to overcome the weight 45 on the arm 22, the plunger 39 moves upwardly to swing said arm on the shaft 31. As soon as the pressure below the diaphragm drops, the weight 20 returns the bar 22 to its lowered position. The swinging movement, which the bar may undergo, may be readily varied by adjusting the limiting bolts 38 and 37 which are adapted to engage the top and bottom of the block 23 secured to the 25 bar.

In order to operate the damper 19 when the bar 22 is swung, a chain, or other flexible connection 50 has one end secured to a collar 51 30 slidably fastened on the arm. The chain passes over a pulley 52 mounted on the side of the boiler housing and has its other end fastened to the control arm 20 of said damper. When the bar 22 is swung, it is evident that the damper arm 20 is also swung through the medium of the 35 chain 50. To vary the movement imparted to the arm 20 by the swinging of the bar 22, it is possible to move the collar 51, to which the chain is secured, along the bar 22, whereby its position to the pivot point 31 is varied, with a resultant 40 variation in stroke or movement imparted to the chain.

45 For actuating the fuel control valve 12 and the air supply louvers 14 at the same time that the damper 19 is adjusted by the swinging of the bar 22, a second actuating bar 53 is provided. This bar is pivoted to a bracket 54 which is secured to the upper end of the pipe 46 and is connected to the master bar 22 by a link 55. As is clearly shown in Figure 1, the link is adjustably secured to the bars so that it may be secured thereto at various points therealong, whereby the stroke or swinging movement of the bar 50 55 may be readily varied. A chain, or other flexible connection, 56 has one end adjustably secured to the outer end of the arm 53 and said chain passes over pulleys 57 which are mounted on the boiler housing. The other end of the chain is secured to an arm 58 which is fastened on a shaft 59 rotatably mounted in brackets 60. The shaft has a radial arm 62 which is connected by a chain, or other flexible connection, 63 with the control arms 16 of the louvers. A second radial arm 64 is secured to the shaft and has connection through a chain 65, which passes over 65 a pulley 66', with the control arm 13 of the fuel supply valve 12. When the shaft 59 is rotated, the louvers 14 and the fuel supply valve 12, are adjusted.

70 From the foregoing, it will be manifest that when pressure is applied to the diaphragm 40, the plunger 39 is lifted, whereby the master control bar 22 is swung. The swinging of the bar adjusts the damper 19 through the chain 50 and at the same time moves the bar 53 which adjusts 75

the louvers 14 and valve 12 by rotating the shaft 59 through the medium of the chain 56. Therefore, all three elements, the valve 12, louvers 14 and damper 19, are simultaneously adjusted to efficiently control the operation of the boiler.

The pressure which operates the diaphragm 40 may be conducted to the lateral pressure line 49 from any suitable source, but it is preferable that the boiler pressure be utilized to operate the diaphragm. By using the boiler pressure to control the diaphragm, which, in turn, controls the bar 22, it will be seen that the various elements which effect the operation of the boiler are automatically controlled in accordance with the boiler conditions. The pressure from within the boiler may be conducted therefrom by a pressure line or pipe 70 which has one end connected in the top of the boiler housing. The other end of the line 70 may, if desired, be connected with the line 49 whereby the boiler pressure is conducted directly to the diaphragm 40. If this hook up is used, the weight 45 on the free or outer end of the bar 22 is properly adjusted so that when a predetermined pressure is attained within the boiler, the diaphragm 40 is lifted to swing the bar 22. Swinging of the bar will reduce the fuel supply and will also adjust the air supply louvers 14 and the damper 19, whereby the boiler output is cut down. Whenever the pressure within the boiler drops below a predetermined point, as determined by the adjustment of the weight 45, the bar 22 is returned to its original or lowered position, whereby the valve 12, louvers 14 and damper 19 are adjusted to step up or increase the boiler output. In this manner, a predetermined or fixed pressure may be automatically maintained at all times within the boiler.

Although it is possible, as has been explained, to connect the line 70 directly with the pressure line 49 so that the pressure from the boiler is conducted directly to the diaphragm 40, it is not particularly desirable. This is true because the pressure will build up slowly below the diaphragm 40 and will gradually move said diaphragm upwardly, whereby the bar 22 is gradually swung to an upward position, which results in a gradual adjustment of the various elements which affect the boiler operation. It is preferable that the diaphragm be moved upwardly immediately so as to swing the bar in a continuous motion from a lowered to a raised position.

To accomplish this operation of the diaphragm and bar and to eliminate the gradual upward movement thereof, a pilot mechanism A is interposed between the line 70 which leads from the boiler and the line 49 which is connected to the diaphragm case. This pilot mechanism is clearly shown in Figure 7 and includes a tubular body 71 which is formed with an annular external flange 72 at its upper end. A diaphragm 73 overlies the flange 72 and is clamped between said flange and a second flange 74 which is formed at the base of a vertically extending cage 75. A coil spring 76 has its lower end resting on the upper surface 65 of the diaphragm 73, while the upper end of the coil spring is engaged by an adjusting screw 77 which is threaded to the top of the cage. By adjusting the screw 77, it is manifest that the tension on the spring may be varied and since said spring is exerting its pressure against the diaphragm, it is manifest that the amount of pressure necessary to raise said diaphragm may be varied by adjusting said screw.

An axial stem 78 depends from the diaphragm 73, extending through the bore of the body 71

and the lower end of said stem carries a conical valve member or pin 79. The pin 79 is adapted to close a port 80 which is formed within a flow bean 81 mounted within the bore 82 of a block 83. The block 83 is flanged at its upper end and 5 is fastened to a flange formed at the lower end of the body 71. An outlet line 84 is connected in the bore 82 of the block and a T 85 is connected with said line. The lateral pressure line 49 which leads from the T 47 below the diaphragm 40 has 10 its opposite end connected in the T 85 whereby when the valve pin 79 is unseated, communication between the bore of the body 71 and the diaphragm case 34, is established.

The pressure line 70 from the interior of the 15 boiler 10 has its other end connected in a radial port 86 which is formed in the body 71, whereby the boiler pressure is conducted into the bore of said body beneath the diaphragm 73. Normally, the diaphragm is in a lowered position, being held 20 so by the spring 76, whereby the valve pin 79 carried by the diaphragm stem 78 is in a seated position. Therefore, the pressure entering the bore of the body 71 through the line 70 is trapped within said bore and acts against the diaphragm 25 73. As soon as this pressure overcomes the pressure of the spring 76, the diaphragm 73 moves upwardly to raise the stem 78 and unseat the valve 79. As soon as this occurs, the pressure within the line 70 and bore of the body 71 may 30 flow through the port 80, line 84, T 85, line 49 and finally through the pipe 46 into the diaphragm case 34 below the diaphragm 40. The adjustment of the spring 76 is such that the valve pin 79 is unseated only when sufficient pressure has 35 been built up to actuate the diaphragm 40 to move the same to its upper position. Therefore, as soon as the valve pin 79 opens the port 80, the pressure is directed against the diaphragm 40 and the master bar 22 is immediately swung to 40 its raised position.

When the pressure within the boiler 10 falls below a predetermined point, the diaphragm 40 moves downwardly to return the master bar 22 to its lowered position. The pressure drop within 45 the bore of the body 71 permits the diaphragm 73 to be moved downwardly by the spring 76, whereby the valve pin 79 is again seated to close the port 80 and cut off communication between the body 71 and the diaphragm case 34. Any pressure which might be trapped between the diaphragm 40 and the valve pin 79, which is within 50 the line 49, may escape through a bleeder 87 which is connected in the latter line. This bleeder comprises a tubular header 88 having a bean 89 in 55 its lower end. The bean is provided with a reduced port 90 which communicates with the bore of the header, whereby pressure within the line 49 may escape upwardly into said bore. A radial port 91 is formed in the upper end of the header 60 and leads from the bore thereof and a suitable discharge pipe 92 may be screwed into the bore 91 to conduct the pressure from the bore of the header. It is pointed out that the size of the port 90 is sufficiently small so that very little pressure 65 can escape therethrough. Therefore, when the pressure is operating the diaphragm, the small amount of pressure through the bleeder port 90 does not affect the normal operation of the device.

It has been found that the various parts of the 70 pilot A may corrode and must be cleansed by means of a suitable chemical, or other substance. In order to keep the valve pin 79 and its associate parts clean, a suitable cleaning substance may be introduced into the bore of the body 71 through 75

5 a conductor 93. A control valve 94 is mounted in the conductor and above said valve a container 95 for holding the cleaning substance, is located. When the valve 94 is opened, the substance flows 10 downwardly through the pipe 93 and into the bore of the body 71, whereby it contacts the valve pin and its associate parts. The cleaning substance may be drained from the bore of the body 71 through an angular outlet port 96 which has 15 a suitable pet cock or valve 97 at its outer end.

10 From the foregoing, it will be seen that the pilot A provides a means whereby a predetermined pressure must be built up within the boiler 10 and the line 70, before such pressure is conducted 15 to the diaphragm 40 which operates the master bar 22. A suitable hand valve 98 may be connected in the pressure line 70 in advance of the pilot A, whereby the flow of pressure through this line may be readily controlled. Also, if desired, a strainer 99 may be mounted in the line 70 20 so as to prevent foreign matter from entering the pilot A. Although it is desirable to employ the pilot, it is again pointed out that said pilot may be eliminated, in which case the line 70 will 25 be connected directly with the pressure line 49 leading to the diaphragm 40.

What I claim and desire to secure by Letters Patent, is:

30 1. A control mechanism for a boiler having a fuel supply valve, an air supply control and a flue damper including, a master control bar, having one end pivoted to a support at one side of the boiler, means slidably mounted on the bar and movable to various positions thereon so as to 35 change its location relative to the pivot point of the bar, said means being arranged to be locked in any of its adjusted positions, a flexible connection between said means and the damper of the boiler, whereby swinging of the bar adjusts said 40 damper, a secondary control lever having one end pivoted to a support and spaced from the master control bar, a connecting link between the control bar and lever so that swinging of the bar results in a swinging of the lever, means for ad- 45 justably connecting the ends of the link to the bar and lever, whereby said link may be connected to these elements at any point thereon with respect to their pivots, flexible connecting means between the secondary lever and the fuel 50 supply valve and the air supply control, whereby swinging of the lever actuates the valve and control, and pressure responsive means for swinging the master control bar to actuate the damper and also to swing the lever to operate the fuel 55 valve and air control.

55 2. A control mechanism for a boiler having a fuel supply valve, an air supply control and a flue damper including, a master control bar, having one end pivoted to a support at one side of the 60 boiler, means slidably mounted on the bar and movable to various positions thereon so as to change its location relative to the pivot point of the bar, said means being arranged to be locked in any of its adjusted positions, a flexible con- 65 nection between said means and the damper of the boiler, whereby swinging of the bar adjusts said damper, a secondary control lever having one end pivoted to a support and spaced from the master control bar, a connecting link between the 70 control bar and lever so that swinging of the bar results in a swinging of the lever, means for adjustably connecting the ends of the link to the bar and lever, whereby said link may be connected to these elements at any point thereon with respect to their pivots, flexible connecting 75

means between the secondary lever and the fuel supply valve and the air supply control, whereby swinging of the lever actuates the valve and control, pressure responsive means for swinging the master control bar to actuate the damper and also to swing the lever to operate the fuel valve and air control, a conductor leading from the boiler to the pressure responsive means for conducting a pressure to said means, whereby the pressure responsive means is operated in accordance with the pressure in the boiler. 10

3. A control mechanism for a boiler having a fuel supply valve, an air supply control and a flue damper including, a master control bar, having one end pivoted to a support at one side 15 of the boiler, means slidably mounted on the bar and movable to various positions thereon so as to change its location relative to the pivot point of the bar, said means being arranged to be locked in any of its adjusted positions, a flexible connection between said means and the damper of the boiler, whereby swinging of the bar adjusts said damper, a secondary control lever having one end pivoted to a support and spaced from the master control bar, a connecting link be- 20 tween the control bar and lever so that swinging of the bar results in a swinging of the lever, means for adjustably connecting the ends of the link to the bar and lever, whereby said link may be connected to these elements at any point thereon with respect to their pivots, a collar slidably mounted on the control lever and movable to any position thereon with respect to the pivot point of said lever, said collar being arranged to be locked in its various adjusted positions, a flexible 25 connection having one end secured to the collar with its other end operatively connected to the fuel supply valve and air supply control, whereby swinging of the lever actuates the valve and control, and pressure responsive means associated 30 with the master control bar for swinging the same to actuate the damper and also to swing the lever and operate the fuel valve and air control. 35

4. A control mechanism for a boiler having a fuel supply valve, an air supply control and a flue damper including, a master control bar, having one end pivoted to a support at one side of the boiler, means slidably mounted on the bar and movable to various positions thereon so as to change its location relative to the pivot point of the bar, said means being arranged to be locked in any of its adjusted positions, a flexible connection between said means and the damper of the boiler, whereby swinging of the bar adjusts said damper, a secondary control lever having one end pivoted to a support and spaced from the master control bar, a connecting link between the control bar and lever so that swinging of the bar results in a swinging of the lever, means for adjustably connecting the ends of the link to the bar and lever, whereby said link may be connected to these elements at any point thereon with respect to their pivots, flexible connecting means between the secondary lever and the fuel supply valve and the air supply control, whereby 40 swinging of the lever actuates the valve and control, a cylinder disposed below the master control bar and having a pressure responsive element in its lower end, a plunger of smaller diameter than the cylinder mounted in said cylinder above 45 the pressure responsive element, said piston having a point contact with the underside of the control bar, a weight adjustably mounted on the outer end of the bar for holding the bar in contact with the piston, and means for conducting 50

a pressure to the underside of the pressure responsive element to move the piston upwardly and thereby swing the control bar to actuate the damper and to swing the control lever and thereby operate the fuel valve and air control.

5. A control mechanism for a boiler having a fuel supply valve, an air supply control and a flue damper including, a master control bar, having one end pivoted to a support at one side of the boiler, means slidably mounted on the bar and movable to various positions thereon so as to change its location relative to the pivot point of the bar, said means being arranged to be locked in any of its adjusted positions, a flexible 10 connection between said means and the damper of the boiler, whereby swinging of the bar adjusts said damper, a secondary control lever having one end pivoted to a support and spaced from the master control bar, a connecting link between the control bar and lever so that swinging of the bar results in a swinging of the lever, means for adjustably connecting the ends of the link to the bar and lever, whereby said link may be connected to these elements at any point 15 thereon with respect to their pivots, flexible connecting means between the secondary lever and the fuel supply valve and the air supply control, whereby swinging of the lever actuates the valve and control, a cylinder disposed below the master 20 control bar and having a pressure responsive element in its lower end, a plunger of smaller diameter than the cylinder mounted in said cylinder above the pressure responsive element, said piston having a point contact with the underside 25 of the control bar, a weight adjustably mounted on the outer end of the bar for holding the bar in contact with the piston, a conductor leading from the boiler to the pressure responsive element for conducting a pressure to said element 30 whereby the element and piston are actuated in accordance with the boiler pressure, and a valve interposed between the boiler and pressure responsive element for controlling the pressure passing to said means.

40. 6. A control mechanism for a boiler having a fuel supply valve, an air supply control and a flue damper including, a master control bar, having one end pivoted to a support at one side of the boiler, means slidably mounted on the bar and movable to various positions thereon so as to change its location relative to the pivot point of the bar, said means being arranged to be locked in any of its adjusted positions, a flexible connection between said means and the damper of the boiler, whereby swinging of the bar adjusts 45 said damper, a secondary control lever having one end pivoted to a support and spaced from the master control bar, a connecting link between the control bar and lever so that swinging of the bar results in a swinging of the lever, means for 50 adjustably connecting the ends of the link to the bar and lever, whereby said link may be connected to these elements at any point thereon with respect to their pivots, flexible connecting means between the secondary lever and the fuel supply valve and the air supply control, whereby 55 swinging of the lever actuates the valve and control, a cylinder disposed below the master control bar and having a pressure responsive element in its lower end, a plunger of smaller diameter than the cylinder mounted in said cylinder above the pressure responsive element, said piston having a point contact with the underside of the control bar, a weight adjustably mounted on the outer end of the bar for holding the bar in contact with the piston, a conductor leading from the boiler to the pressure responsive element for conducting a pressure to said element whereby the element and piston are actuated in accordance with the boiler pressure, a valve seat at the lower end of the housing, a plunger valve movable within the housing and adapted to engage the seat, and a diaphragm at the upper end of the housing and connected with the plunger valve, said diaphragm being constantly exposed to the boiler pressure whereby said pressure acting thereagainst raises the valve to admit the pressure through the conductor to the pressure responsive element.

5. in contact with the piston, a conductor leading from the boiler to the pressure responsive element for conducting a pressure to said element whereby the element and piston are actuated in accordance with the boiler pressure, a valve interposed between the boiler and pressure responsive element for controlling the pressure passing to said means, and pressure actuated means for controlling the position of the valve, whereby a predetermined pressure must be built up in the boiler before said pressure is conducted to the pressure responsive element.

7. A control mechanism for a boiler having a fuel supply valve, an air supply control and a flue damper including, a master control bar, having one end pivoted to a support at one side of the boiler, means slidably mounted on the bar and movable to various positions thereon so as to change its location relative to the pivot point of the bar, said means being arranged to be locked in any of its adjusted positions, a flexible connection between said means and the damper of the boiler, whereby swinging of the bar adjusts said damper, a secondary control lever having one end pivoted to a support and spaced from the master control bar, a connecting link between the control bar and lever so that swinging of the bar results in a swinging of the lever, means for adjustably connecting the ends of the link to the bar and lever, whereby said link may be connected to these elements at any point thereon with respect to their pivots, flexible connecting means between the secondary lever and the fuel supply valve and the air supply control, whereby swinging of the lever actuates the valve and control, a cylinder disposed below the master control bar and having a pressure responsive element in its lower end, a plunger of smaller diameter than the cylinder mounted in said cylinder above the pressure responsive element, said piston having a point contact with the underside of the control bar, a weight adjustably mounted on the outer end of the bar for holding the bar in contact with the piston, a conductor leading from the boiler to the pressure responsive element for conducting a pressure to said element whereby the element and piston are actuated in accordance with the boiler pressure, a valve seat at the lower end of the housing, a plunger valve movable within the housing and adapted to engage the seat, and a diaphragm at the upper end of the housing and connected with the plunger valve, said diaphragm being constantly exposed to the boiler pressure whereby said pressure acting thereagainst raises the valve to admit the pressure through the conductor to the pressure responsive element.

8. A control mechanism for a boiler having a fuel supply valve, an air supply control and a flue damper including, a master control bar, having one end pivoted to a support at one side of the boiler, means slidably mounted on the bar and movable to various positions thereon so as to change its location relative to the pivot point of the bar, said means being arranged to be locked in any of its adjusted positions, a flexible connection between said means and the damper of the boiler, whereby swinging of the bar adjusts said damper, a secondary control lever having one end pivoted to a support and spaced from the master control bar, a connecting link between the control bar and lever so that swinging of the bar results in a swinging of the lever, 60

means for adjustably connecting the ends of the link to the bar and lever, whereby said link may be connected to these elements at any point thereon with respect to their pivots, flexible connecting means between the secondary lever and the fuel supply valve and the air supply control, whereby swinging of the lever actuates the valve and control, a cylinder disposed below the master control bar and having a pressure responsive element in its lower end, a plunger of smaller diameter than the cylinder mounted in said cylinder above the pressure responsive element, said piston having a point contact with the underside of the control bar, a weight adjustably mounted on the outer end of the bar for holding the bar in contact with the piston, a conductor leading from the boiler to the pressure responsive element for conducting a pressure to said element where-

by the element and piston are actuated in accordance with the boiler pressure, a tubular housing connected in the conductor between the boiler and said means, a valve seat at the lower end of the housing, a plunger valve movable within the housing and adapted to engage the seat, a diaphragm at the upper end of the housing and connected with the plunger valve, said diaphragm being constantly exposed to the boiler pressure whereby said pressure acting thereagainst raises the valve to admit the pressure through the conductor to the pressure responsive means, and a coiled spring above the diaphragm for urging the same downwardly against the boiler pressure, whereby a predetermined pressure must be present to lift the valve and admit pressure to said pressure responsive means.
